Fig. 14.

A technical line drawing of a mechanical component. A vertical cylindrical part, labeled 51, is shown. At the top, it features a pulley 56 with a gear-like top edge. A central vertical rod, labeled 53, is positioned within the cylinder 51. The rod 53 has a ribbed piston 55 attached to its upper portion. A horizontal beam or rod, labeled 52, is attached to the lower part of the cylinder 51. The beam 52 has a gear-like bottom edge and a circular component 54 attached to its lower end. The entire assembly is shown in perspective, with the cylinder 51 oriented vertically.

UNITED STATES PATENT OFFICE

LYTLE S. ADAMS, OF WASHINGTON, DISTRICT OF COLUMBIA

SYSTEM OF RAILWAY MAIL COLLECTION

Application filed December 31, 1930. Serial No. 505,883.

This invention relates to the use of railway cars, and more especially subway cars, for collecting mail and delivering it at a postal station on the line, and aims to provide automatic means for so doing, thereby permitting frequent collections to be made and relieving the streets of some of the vehicular traffic that has been required heretofore for mail collections.

10 Objects of the invention are to increase the utility of subway cars in large cities by adapting them for collecting letter mail and light packages from passengers, street collection boxes and building mail chutes along the sub-
15 way, and to provide suitable means on the cars and along the track for mutual cooperation to deliver loose mail to a moving car and discharge it therefrom at a receiving station by means operated automatically by the
20 movement of the car.

Further objects of the invention are to provide frequent mail collection service at a minimum cost, thereby expediting the service and supplementing the air mail in providing
25 a more rapid delivery, and to enable the transportation company to increase its revenue with very little additional operating cost.

Other objects and advantages of the invention appear in connection with the following description of an illustrative embodiment as shown in the accompanying drawings, wherein

Fig. 1 is a side view of a standard subway car used in cities on the eastern seaboard of the United States, provided with mail collecting equipment of a preferred type;

Fig. 2 is a part plan and part horizontal section on line 2—2 of the car shown in Fig. 1;

40 Fig. 3 is a transverse cross-section of the same on line 3—3 in Fig. 2;

Fig. 4 is a transverse vertical section through the roof of a subway illustrating the arrangement of a mail chute to discharge
45 into a suitable receptacle on the car below;

Fig. 5 is a lengthwise vertical section of the same, showing the detail construction of the lower end of the discharging chute and upper portion of the receiving hopper or chute
50 on the car, showing the parts about to en-

gage upon movement of the car in the direction of the arrows;

Fig. 6 is a similar view looking at the car from the opposite side;

Fig. 7 is an enlarged transverse section of the same, showing the chute closure and roof trap parts in mail delivering position;

Fig. 8 is a vertical section of the same on the line 8—8 in Fig. 7;

Fig. 9 is a plan view of the track and stationary mail receiving hopper showing the lower end of the car chute in cross-section on the line 9—9 in Fig. 10;

Fig. 10 is a vertical longitudinal section of the same on the line 10—10 in Fig. 9;

Fig. 11 is a vertical cross-section on the line 11—11 in Fig. 10 of the track hopper and lower end of the car chute, showing the parts in mail delivering position;

Fig. 12 is an enlarged view of the end of the track hopper, showing the parts in normal position in full lines, and in mail discharging position in dotted lines;

Fig. 13 is a vertical longitudinal section through the lower end of the car receptacle and side view of the track hopper, showing the car bottom door and hopper door in closed position;

Fig. 14 is a partial side view of the track hopper, etc. looking at the opposite side from Fig. 13;

Fig. 15 is a transverse vertical section of the lower part of the car and track, showing the track hopper in end elevation, on the line 15—15 in Fig. 14, the operating parts being shown in mail discharging position; and

Fig. 16 is a part side view and part cross-section of a detail of the apparatus illustrated in Fig. 13, to a larger scale.

As is well known, the cars or trains operated in subways in large cities are dispatched on a fast schedule at frequent intervals, so that a large number of cars or trains pass a given point in an hour, thus making possible collections from chutes and receptacles located along the line at very frequent intervals. My invention contemplates locating discharge hoppers at convenient points along the line to receive the mail collected by the cars, thereby securing an almost continuous

flow of mail matter from widely distributed deposit points to postal receiving stations, entirely by automatic means.

To this end I have devised equipment comprising stationary receptacles or chutes 20 (see Fig. 4) spaced along the roof 21 of the subway, in which the mail may be deposited, car receptacles 22 each provided with a funnel or hopper 23 at its upper end to receive mail from the receptacles 20 and adapted to discharge at its lower end into one or more track hoppers 24 (see Fig. 1) preferably positioned between the track rails 25. The car receptacles may be located centrally in the cars, as illustrated, or wherever convenient.

In the illustrated apparatus, each stationary receptacle or chute 20 is provided with a gate 26 at its lower end and a second gate 27 spaced above its lower end. These gates 26, 27, may be pivoted or otherwise arranged to open and close in alternation, that is, when the lower gate is in its usual closed position the upper gate is open, and vice versa, as illustrated in Figs. 7 and 8, thereby preventing an undue discharge of mail at a time. The gates 26, 27, are actuated by the moving car through any convenient means, that illustrated comprising a gear sector 28 on the pivot shaft of the gate 26 meshing with a sector 29 on an operating shaft 30 having an arm 31 provided with a roller 32 adapted to be engaged and lifted by the angle plate 33, which is mounted on the outside of one side wall of the hopper 23 on the car. The upper gate is connected to the sector 29 by means of a link 34 connected through a spring relief device 35 with the arm 36 on the pivot shaft of the gate 27. The spring relief device contains a compression spring 37 so disposed as not to interfere with the opening of the upper gate when the lower gate closes, but to permit the lower gate to open without closing the upper gate should it be jammed for any reason. A spring 38 attached to the gear sector 29 normally holds the lower gate closed and the upper gate open. These operating parts are suitably housed in a casing 40 on the outside of the chute 20.

The lower end of the chute 20 is provided with a flexible tube 41 of canvas or other suitable material to guide the mail into the hopper 23, this tube being long enough to extend between its side walls, which project above the end walls, as shown in Fig. 7, to prevent mail from spilling over the side of the hopper between it and the lower end of the chute. The length of the hopper is sufficient to prevent mail from spilling over its ends during the time that the lower gate 26 is open, the track 33 being substantially shorter than the hopper to shorten the space interval that the gate 26 is open.

The hopper 23 is provided with hinged doors or covers 43, 44, pivoted lengthwise of its side walls to open downwards when the car moves beneath the chute 20, as indicated

in full lines in Fig. 7. Any convenient mechanism may be utilized for this purpose, that shown comprising gear sectors 45 on the ends of the pivot shafts for the doors, which mesh together to cause the doors to swing in unison. One of the pivot shafts has fixed to its end a small gear segment 46 which meshes with a large gear segment 47 loosely pivoted on the corresponding end of the other pivot shaft and provided with an operating arm 48. A spring 49 holds the arm up to normally keep the doors closed. Similar gear sectors and operating arms are provided at each end of the hopper 23, connected by a rail or track 50, which is adapted to engage under and be depressed by a roller 51 carried by a pivoted mounting 52 secured to the lower end of the chute 20, or other stationary support, as illustrated in Fig. 6, to open the doors 43, 44.

The mounting 52 and roller 51 are normally held in proper position to engage and depress the cam rail by means of a spring relief strut 53, shown in Fig. 16. This strut comprises a link 54 pivoted to the mounting arm 52 and carrying a spring case within which the spring 55 is held compressed by an adjusting rod 56. The upper end of the adjusting rod 56 is pivoted to a fixed part of the roof structure. Lock nuts 57 hold the adjusting rod in its proper relation to the link 54 to adjust the length of the strut to hold the arm 52 and roller 51 at the proper elevation to actuate the hopper doors 43, 44, when the car moves the latter beneath the chute 20. Should any obstruction strike the roller 51 or arm 52 the spring 55 would give and permit the strut 53 to shorten, thus preventing any mishap to the apparatus.

The track hopper 24 and actuating means for the gate 60 at the lower end of the car receptacle 22 and doors 61 covering the hopper opening may be similar in construction to the corresponding parts of the chute 20 and car hopper 23 (see Figs. 9 to 15, inclusive). The gate 60 is preferably actuated by a gear sector 62 meshing with a second gear sector 63 pivoted to the lower end of the chute 22 and provided with an arm 64 and roller 65 for engagement with the angle track 66 on the side wall of the hopper. The hopper doors 61 are pivoted upon lengthwise shafts 67 having meshing gear sectors 68 at their ends to cause them to swing down and back together. Upon the ends of one of the shafts 67 are fixed small gear sectors 69, and loosely pivoted on the ends of the other shaft 67 are large gear sectors 70 meshing with the sectors 69. Arms 71 carried by the gear sectors 70 have a roller track 72 fixed to their ends for actuating the gear sectors when the car passes over the hopper 24, the springs 73 enclosed in the telescoping housings 74 pivoted on the ends of the shaft 67 normally holding the hopper doors in closed position. The actuating means on the car for opening the hopper

doors comprises a roller 75 on a pivoted arm 76 maintained in proper position by a spring strut 77 similar to the spring strut 53.

5 A flexible extension 78 is secured on the lower end of the receptacle 22, to guide loose mail into the hopper. The receptacle may also be fitted with letter drop slots 79 within the car for the convenience of passengers.

10 As shown in Fig. 7, the side walls of the hoppers may be provided with slots 80 immediately above the door pivot shafts to permit dirt, water and debris to pass off the doors and outside of the hopper, the doors sloping towards the slots for this purpose; and the 15 doors may advantageously be shaped to interengage along their edges to prevent rain and snow and dirt from getting into the hopper.

15 A draft deflector 81 may advantageously be fitted to the lower end of the receptacle 23 to provide a downward current of air around 20 the mouth of the receptacle tending to suck air through it from the top end and aid in delivering loose mail into the hopper in the track.

25 For the accommodation of street mail collectors a deposit chute 85 may be provided on the chute 20 at a convenient height above the sidewalk to receive mail from the collector's wagon or pouch. It is contemplated that these chutes will be located near stopping points of the cars so as to reduce wear and tear on the equipment due to unduly high running speed.

30 The operation of the equipment is entirely automatic from the time the mail or package is deposited in the roof chute 20 until it is discharged into a track hopper 24, the movement of the car causing the gates in the chutes and hopper doors to open and close at the proper times for the respective cars to pick up and deliver such mail as collects in the stationary receptacles in the interim.

35 Means are provided for preventing injury to the parts of the apparatus should moving parts foul fixed parts or something go wrong, and for keeping the weather out of the receptacles and chutes. The working parts are few and easily accessible for inspection and repair. There are no motors or other continuously running parts requiring frequent attention. No radical changes or rearrangement of essential constructional or operating features in the car or track are required in order to apply the invention thereto, which 50 may be done without interfering with the regular operation of the system in other respects.

55 Although the invention is illustrated in connection with a particular type of car, it is not restricted thereto, as it is evident that it is adapted for any desired type of car and kind of service, and the mechanical construction may be varied to suit conditions. The system may be expanded without limit as the 60 need arises.

I claim the following as my invention:

1. A system of mail or package collection comprising a succession of moving cars on a track, stationary chutes located along the track and adapted to discharge into the path of movement of the cars, a hopper on each car adapted to receive articles from said chutes, control gates on said chutes and hoppers having means actuated by movement of individual cars to open said gates in synchronism and means for closing said gates automatically. 70

2. A system of mail or package collection comprising a succession of moving cars on a track, stationary chutes located along the track and adapted to discharge into the path of movement of the cars, a hopper on each car adapted to receive articles from said chutes, a receiving station on the track, a discharge chute in said hopper adapted to register with said receiving station, control gates on said receiving station, chutes and hoppers having closures actuated by movement of individual cars to open said closures and gates in synchronism and means for closing said gates 80

85 and closures automatically. 90

3. A system of mail or package collection comprising a succession of moving cars on a track, stationary chutes located along the track and adapted to discharge into the path of movement of the cars, a hopper on each car adapted to receive articles from said chutes, control gates on said chutes and hoppers having means actuated by movement of individual cars to open said gates in synchronism, and means for closing said gates automatically, including spring means arranged to permit opening them when said car actuated means operates. 95

4. A system of mail or package collection for subways comprising spaced chutes discharging into the subway tunnel above the track level, cars provided with hoppers adapted to register with said chutes, closures for said chutes and hoppers, and means actuated by movement of said respective cars for opening said closures when in register with each other, said closures normally being closed. 105

5. A system of mail or package collection for subways comprising spaced chutes discharging into the subway tunnel above the track level, cars provided with hoppers adapted to register with said chutes, said hoppers discharging at near the track level, a stationary receiving receptacle, closures for said receiving receptacle, chutes and hoppers and means actuated by movement of said respective cars for opening said closures when in register with each other, said closures normally being closed. 115

6. A system of mail or package collection for subways comprising spaced chutes discharging into the subway tunnel above the track level, cars provided with hoppers adapted to register with said chutes, a sta- 120

130

- tionary receiving receptacle, closures for said receiving receptacle, chutes and hoppers, and means actuated by movement of said respective cars for opening said closures when in register with each other, said means including springs for permitting movement of said parts to prevent breakage in case of fouling or derangement.
7. In combination with a track and a passenger car running thereon, a fixed chute mounted to discharge above said track, a hopper alongside the track below the discharge level of said chute, and a chute passing through the car for receiving articles from said chute and discharging articles into said hopper.
8. In combination with a track and a passenger car running thereon, a fixed chute mounted to discharge above said track, a hopper alongside the track below the discharge level of said chute, and a chute passing through the car for receiving articles from said chute and discharging articles into said hopper, said last named chute having an opening into it from the car permitting deposit of articles therein by passengers.
9. In combination with a track and a passenger car running thereon, a fixed chute mounted to discharge above said track, a hopper alongside the track below the discharge level of said chute, and a chute passing through the car for receiving articles from said chute and discharging articles into said hopper, said last named chute having an opening into it from the car permitting deposit of articles therein by passengers, and means operated by movement of the car for opening said chutes to control the discharge of articles therefrom.
10. In combination with a track and a passenger car running thereon, a fixed chute mounted to discharge above said track, a hopper alongside the track below the discharge level of said chute, and a chute passing through the car for receiving articles from said chute and discharging articles into said hopper, said last named chute having an opening into it from the car permitting deposit of articles therein by passengers, and means operated by movement of the car for opening said chutes and automatic means for closing them to control the discharge of articles therefrom.
11. In a system of railway mail collection, a car having a hopper at an upper level and chute leading therefrom to a lower level, a closure for said hopper, a gate for said chute, means for normally holding said closure and gate closed, and means for actuating said closure to open when the car passes a fixed point for delivering articles to said hopper.
12. In a system of railway mail collection, a car having a hopper at an upper level and chute leading therefrom to a lower level, a closure for said hopper, a gate for said chute, means for normally holding said closure and gate closed, and means for actuating said closure to open when the car passes a fixed point for delivering articles to said hopper.
- gate closed, and means for actuating said gate to open when the car passes a fixed point for discharging articles from said chute.
13. In a system of railway mail collection, a track running below a street, spaced deposit chutes having openings above said street level and extending below said street level to discharge above said track level, gates for the discharge openings of said chutes, cars on said track and receptacles on said cars, and means on said cars operated by movement thereof for opening said gates when said chutes register with said receptacles.
14. In a system of railway mail collection, a track running below a street, spaced deposit chutes having openings above said street level and extending below said street level to discharge above said track level, gates for the discharge openings of said chutes, gates in said chutes above the discharge openings, means for closing the upper and opening the lower gates simultaneously, cars on said track and receptacles on said cars, and means on said cars operated by movement thereof for opening said lower gates when said chutes register with said receptacles.
15. In a railway mail collection system, a series of collection receptacles located along the track having discharge openings spaced above the track level, cars on the track provided with hoppers below the level of said discharge openings and above the level of the track, covers for said hoppers, said covers being pivoted to swing into said hoppers, springs for holding said covers closed, operating means for opening said covers, and means positioned adjacent said discharge openings for engaging said cover operating means and swinging said covers into open position.
16. In a railway mail collection system, a series of collection receptacles located along the track having discharge openings spaced above the track level, cars on the track provided with hoppers below the level of said discharge openings and above the level of the track, covers for said hoppers, said covers being pivoted to swing into said hoppers, springs for holding said covers closed, operating means for opening said covers, including a roller and track, and means positioned adjacent said discharge openings for engaging said cover operating means and swinging said covers into open position.
17. In a railway mail collection system comprising cars running on a fixed track, hoppers on the cars and chutes spaced above the track level and discharging into said hoppers, said chutes having flexible extremities to avoid injuring said cars in case of fouling, closures for the hoppers means associated with said chutes for opening said closures, and resilient means supporting said closure opening means permitting withdraw-

al thereof to prevent damage in case of fouling a moving car.

18. In a railway mail collection system comprising cars running on a fixed track, hoppers on the cars, and chutes spaced above the track level and discharging into said hoppers, closures for the hoppers, weatherproofing means for said closures, means for opening said closures, and resilient means supporting said closure opening means.
19. A mail collecting apparatus for use on passenger cars traveling fixed routes having established stopping places provided with deposit and collection receptacles, said apparatus comprising an elongated hopper arranged lengthwise of the roof of the car, and a chute leading therefrom through the floor of the car, a weatherproof closure for said hopper and a gate for said chute, and means for opening said closure and gate, respectively, at receiving and discharge stations to cooperate with said deposit and collection receptacles.

20. A passenger car having side doors, a chute extending from the roof to beneath the floor of said car opposite said doors, mail deposit slots in said chute convenient to passengers using said doors, a hopper in the roof discharging into said chute, and a gate below said slots to control the discharge from said chute, and means for actuating said gate.

In testimony whereof, I have signed my name to this specification.

LYTLE S. ADAMS.
